UNITED STATES PATENT OFFICE

JOSEPH H. McEVOY, OF HOUSTON, TEXAS

PUMP PACKING ASSEMBLY AND PACKING RINGS

Application filed September 11, 1928. Serial No. 305,222.

The invention relates to an improved arrangement of the packing disposed about the pump rod and within the pump barrel for that type of pump used in water, oil, sulphur 5 or similar wells.

One of the objects of the improvement is to dispense with the use of hydraulic packing of every type and to substitute therefor an all metal packing assembly.

10 Another object is to so arrange the packing and spacer rings that a lubricant may readily be entrapped.

Another object is to devise a packing assembly which will be adjustable to compensate 15 for wear without being removed from the pump barrel.

A further object is to so arrange the packing and spacer rings either upon the pump rod or upon the pump barrel that they may 20 be readily adjusted and a fluid tight seal be maintained throughout the life of the packing.

Other objects of the present improvements are to provide an improved valve construction, a novel ratchet arrangement to retain 25 the packing in compressed relation, and to manufacture this particular type of packing in several forms in accordance with the demands which may arise.

30 Other and further objects will be readily apparent to those skilled in the art when the following description is considered in connection with the drawings, wherein:—

Fig. 1 is a longitudinal section of a pump 35 showing the improved packing arranged therein.

Fig. 2 is an enlarged view of a portion of a pump similar to Fig. 1 but showing the packing in a different configuration than that of 40 Fig. 1.

Fig. 3 shows another form of packing.

Fig. 4 is an enlarged view of the spring sleeve used to retain the packing in compressed condition.

45 Fig. 5 is a view similar to Fig. 1 but showing the packing carried by the pump rod instead of the pump barrel.

Figs. 6 and 7 show modified forms of this type of packing.

50 Figs. 8 and 9 show an elevation and section

respectively of the lower end of the pump plunger while,

Figs. 10 and 11 show an elevation partly broken away, and a section of the spring sleeve as used in Fig. 5.

The construction shown in Fig. 1 discloses a pump barrel 10 which carries threaded to its lower end a coupling 11 which in turn is threaded to a nipple 12. This nipple 12 is connected to a standing valve assembly 13 of 60 usual construction. The coupling 11 has its upper end terminating in a shoulder 14, and is hollowed internally to provide an annular seat 15 for the packing 16. This packing tends to prevent the passage of sand and grit 65 upwardly around the pump plunger.

Inside the pump barrel 10 the pump plunger or pump rod 20 is adapted to reciprocate. Between the pump plunger and pump barrel is an annular opening which is 70 to be filled with packing material which must maintain a fluid seal between the two members. The packing may be arranged in any of several forms as disclosed by this application. Fig. 1 shows an assembly of spacer 75 rings 21 and packing rings 22. These rings may be arranged as shown with their wedge faces in contact. These rings may be formed as a closed annular ring, they may be split rings or in some instances formed of two or 80 more sections to make up an annular ring. The spacer rings 21 it will be noted are somewhat separated leaving an opening 23. As the packing rings 22 wear away in use the spacer rings are compressed at intervals to 85 eventually fill the space 23 as will be later described.

The spacer rings may be formed of steel, brass or any other suitable metal but are preferably of a metal somewhat harder than the 90 packing rings which may be of babbitt, tin, solder, lead or any suitable metal alloy which may be readily deformed.

The spacer rings 21 as shown have a groove 95 24 at the apex of the face and adjacent the meeting edges of the packing rings. When the entire packer is compressed the tapered faces of the respective rings 21 and 22 tend to slide upon each other which results in compressing the packing to form a fluid tight 100

fit with the pump rod 20. As the packing is compressed the edge of each ring is deformed to enter the groove 24, whereby each ring is then somewhat firmly attached to its respective spacing rings and no one ring is then able to take up all of the movement of the entire assembly.

The lowermost spacer is shown as a half ring and rests upon the shoulder 14 previously described. The uppermost spacer is also a half ring and forms a shoulder 25 upon which is placed the compressing sleeve 26. This sleeve forms a means for retaining the packing assembly in position and has internal and external packing rings thereon as shown at 27 and 28, Fig. 1. Fig. 4 shows an enlarged elevation of the sleeve which is made of spring metal and has longitudinal slits therein thus forming the fingers 30. Each finger 30 has its end flared outwardly and formed with ratchet teeth as at 31. The sleeve may, however, be formed without the slits and a single spring finger punched therefrom to act as a locking member. The inside of the pump barrel 10 has ratchet teeth 32 which correspond to and are adapted to mesh with the aforesaid teeth 31.

The top of the pump plunger 20 has threaded to it the usual valve cage 33, but in this instance the lower end 34 thereof serves a specific function. Fig. 1 shows a pump plunger at a point below its normal working position but still it may be lowered further until the end 34 of the cage 33 contacts with the ledge 35 on the inside of the sleeve 26. It is by means of this structure that the packing assembly is compressed at will. The pump plunger is lowered to a position such as shown in Fig. 1 and then dropped sharply to strike the ledge 35. This drives the sleeve 26 downwardly and compresses the packing rings which as stated are supported on the coupling 14. As the sleeve 26 travels downward the ratchet teeth 31 slide past the teeth 32 of the pump barrel and the packing is thus held in its compressed condition. As the packing rings wear away the sleeve 26 may be again bumped or struck to further compress the packing.

It seems apparent with this construction that a novel assembly has been evolved and that any necessary adjustment of the packing is easily obtained by merely lowering the pump rod as described. The metallic packing used is not subject to deterioration when subjected to hot water which is often encountered and there is nothing in the assembly to be replaced until the packing rings have been completely worn away and the ratchet driven to its lowermost position.

The packing assembly as here shown forms a rigid substantial support for the pump plunger 20 so that any tendency of vibration is avoided. The additional packing rings 27 and 28 prevent sand and grit from entering

the assembly so that wear of the parts is reduced to a minimum.

Fig. 2 shows a broken section of the assembly of Fig. 1 but having spacer and packing rings of a different configuration. The spacer rings as in Fig. 1 may be made of any suitable metal as can the packing rings. The spacer rings are indicated at 40 and may have annular grooves 41 at the top, at the bottom or both top and bottom. The packing ring is formed in a plurality of parts such as the cap rings 42 and 43 which are annular rings having a concentric annular groove upon one side and a ridge upon the other side. When two of these cap rings are placed with the grooves thereof adjacent, a cavity is formed to receive the packing ring 44. The cap members and packing ring are both formed of a readily deformable metal but preferably the ring 44 is softer than the cap rings 42 and 43 whereas the spacer rings 40 are composed of a material harder than either of the others.

This embodiment of the invention is constructed to function the same as that of Fig. 1 as when it is compressed the packing ring 44 will bulge out expanding the cap rings 42 and 43 forming a fluid tight bearing for the pump plunger. The advantage obtained by this construction is that the softer packing metal 44 is confined between walls of harder metal and does not therefore come in contact with the moving plunger rod. This prolongs the life of the packing and results in a material saving.

Fig. 3 shows an embodiment somewhat similar to Fig. 1 but the arrangement of the packing rings and spacers is reversed. 50 indicates a packing ring of rubber of any desired degree of hardness and 51 indicates a metal spacer ring. It will be noted that the spacer ring has an elongated face 52 to contact with the moving plunger rod. By compressing the sleeve of Fig. 1, the rings 50 are expanded forcing the ring 52 into fluid tight engagement with the pump rod. This form of the invention is especially adapted to a worn pump rod where a great deal of expansion is desired and could very well be used to accommodate the next smaller size of pump plunger by merely compressing the sleeve 26.

In combination with the structure just described in Fig. 1 there is shown an improved valve 55 which is shown best at the top of Fig. 5. It has been customary in pumps of this type to provide at the top a ball valve similar to that shown at the bottom of Fig. 1, however, a valve having a cone seat 56 and a stem 57 which is adapted to slide in a sleeve 58, has been found much better in service. Such a valve as shown when pressed to closed position by a spring 59 is at all times held in a perpendicular position and quickly seats when the flow of fluid ceases. With the usual ball valve the fluid, gases and

sand passing tend to set the ball to bobbing around against the seat and the valve cage whereby it is soon worn and a leaking valve results. The valve seat as here shown is a re-

5 movable ring 60 which rests upon a coupling 61 threaded to the pump rod. The valve cage 33 is threaded onto the coupling 61 and has a shoulder to engage the ring 60 and hold it firmly in position.

10 Fig. 5 also shows a form which the invention may take in that the packing rings, spacer rings, and ratchet sleeve are carried by the plunger and the moving surface is between the packing rings and the pump barrel.

15 The form shown in Fig. 5 is somewhat similar to the form of Fig. 2 but the cap rings 65 and 66 have been modified to cover only one side and one edge of the packing ring 67.

20 Thus the packing ring rests in constant engagement with the plunger 70, and the harder metal 65 and 66 takes the wear with the barrel 71. The spacer rings 72 have been altered to meet the existing conditions, namely, several oil grooves 73 have been provided

25 to trap lubricant and to prevent the passage of sand or grit. The internal surface of the spacer ring 72 has been hollowed out as at 74.

30 The construction of the ratchet sleeve is similar to that of Fig. 1 except the sleeve 76 is carried by the pump plunger 70 and the ratchet teeth 77 are formed on the plunger at 78. Having reference to Figs. 8 to 11, enlarged views of the sleeve and ratchet are

35 shown. The ratchet teeth are here shown as a series of threads 77 which may either be right or left handed as desired. A longitudinal groove 79 is formed in the plunger which acts as a lock in conjunction with the finger

40 80 of the sleeve 76.

45 A special coupling 83 is shown connecting the pump barrel and the nipple there below and has an inwardly projecting shoulder 84 upon which the ledge 85 of the sleeve 76 is adapted to be struck the same as in the arrangement of Fig. 1. A separate ring may be provided to take the place of the integral shoulder 84 if desired. If this is provided it is held in place by the adjacent ends of the 50 pump barrel, and nipple as well as the coupling 83.

55 In this form of the ratchet sleeve it is preferable that any compressing of the packing rings be done by screwing the sleeve 76 onto the threads 77. To accomplish this the pump rod is lowered until the weight rests upon the shoulder 84 and the ledge 85, the plunger is then rotated and the weight compresses the packing and permits rotation of the plunger 60 in the sleeve 76. It is to be understood that either the ratchet of Fig. 1 or the threaded arrangement of Fig. 5 may be employed.

65 Fig. 6 shows a further embodiment of the packing assembly as adapted for use in Fig. 5, namely it is to be carried by the pump

plunger instead of the casing. This disclosure is the exact counterpart of Fig. 1. The spacer rings 88 and packing rings 89 being reversed as to their position.

70 Fig. 7 shows a still further modification also adapted for the Fig. 5 construction, here the spacer rings 90 are made of brass or some similar hard metal, the packing rings 93 are made of either hard or soft rubber or any suitable composition. It will be noticed that both the spacer rings and the packing rings are stepped at 94 to interfit, and that the elongated contact face of the spacer ring is adjacent the pump barrel to take the wear. The packing rings 93 have on their inner 75 surface a shim 92 which may be of brass, this shim 92 contacts with one of the steps 94 of the spacer ring 90. Thus when the sleeve 76 is screwed or bumped over the ratchet teeth the shim 92 shears off of the step 94 to the next step and allows the rubber packing ring 93 to firmly press it into engagement with the pump rod.

80 The several figures of the drawings illustrate staggered sets of rings in most instances but for the purposes of this improvement the entire assembly may if desired be made of packing rings and the spacer rings dispensed with. In the event this form is adopted the packing rings would have co-acting grooves 85 and recesses as shown in Fig. 2 on the cap and spacer rings. Either the packing or the spacer rings may be formed in rings similar to the spacing rings of Fig. 2 if desired.

85 The spring sleeve of Figs. 4 and 10 may be if desired formed other than here illustrated in that any number of fingers may be provided or as stated the sleeve may be tubular and a single indented or outwardly pressed finger formed thereon. The ratchet teeth of Fig. 4 or the threaded arrangement of Fig. 8 may be adopted as desired.

90 Fig. 1 shows the cooperating shoulders to compress the packing at the top of the assembly, whereas Fig. 5 shows it at the bottom, either may be used as the occasion demands without departing from the spirit of the invention.

95 It is believed that from the foregoing description those skilled in the art will be enabled to practice the improvement which may readily take embodiments other than here shown without departing from the spirit of the invention.

100 Having described the invention, what is claimed is:

1. In a pump, alternate packing and spacing rings, each packing ring being elongated adjacent the inner side and of shorter length on its outer side, said spacing rings 105 being shaped to interfit between said packing rings and formed with a plurality of shoulders, and an inner sleeve on said packing rings to engage one of said shoulders on 110 said adjacent spacing rings.

2. In a pump, alternate packing and spacing rings, each packing ring being elongated adjacent the inner side and of shorter length on its outer side, said spacing rings being shaped to interfit between said packing rings and formed with a plurality of shoulders, and an inner sleeve on said packing rings to engage one of said shoulders on said adjacent spacing rings, said sleeve being adapted to be faced from one shoulder to another on said spacing sleeve when said rings are moved longitudinally together and means to force said rings toward each other.
3. In a pump, a pump barrel, a pump plunger therein a packing assembly including alternate packing and spacing rings between said pump barrel and said plunger, said rings having elongated portions on one side and shorter portions on the opposite side to interfit with adjacent rings, and a sleeve at one end of said packing assembly said sleeve fitting between said plunger member and said barrel member and spring fingers on said sleeve provided with ratchet teeth engaging one of said members to resist longitudinal movement away from said packing but allowing compression of said packing rings.
4. A pump including a pump barrel, a plunger in said barrel, a packing assembly between said plunger and said barrel supported upon said plunger, a sleeve on said plunger below said packing, spring arms on said sleeve having ratchet teeth thereon, said plunger having ratchet teeth cooperating therewith to prevent said sleeve from downward movement thereon, and means on said pump barrel cooperating with said sleeve to move said sleeve to compress said packing rings longitudinally.

In testimony whereof I hereunto affix my signature this 28th day of August, A. D. 1928.

JOSEPH H. McEVOY.
